INVENTOR

MILO D. RATHBUN

BY Thomas K. Ryan
ATTORNEY.

UNITED STATES PATENT OFFICE.

MILO D. RATHBUN, OF MUNCIE, INDIANA.

RADIATOR CAP DEVICE.

Application filed January 12, 1923. Serial No. 612,215.

To all whom it may concern:

Be it known that I, MILO D. RATHBUN, a citizen of the United States, residing at Muncie, in the county of Delaware and State 5 of Indiana, have invented certain new and useful Improvements in Radiator Cap Devices, of which the following is a specification.

This invention relates to improvements in 10 cap-devices for automobile radiators.

The improved form of radiator cap-device now used for automobile radiators is not only ornamental and capable of being opened and closed, but it is the means of support 15 for the moto-meter device. Such improved form of radiator cap, besides being very practicable, is attractive, and of specific value as an accessory to any type or class of automobile. To guard against the detaching 20 or the removal of the radiator cap-device by unauthorized persons, it is desirable that the device may be rigidly locked or secured at its position.

To provide a cap-device of rugged and 25 durable construction and which said device when secured to the radiator nozzle becomes locked thereon, is the object of the present invention.

The objects of my invention are accomplished by and the invention is embodied in 30 the new and improved construction, combination and arrangement of parts, shown in the accompanying drawings. The several parts of the invention are identified by suitable characters of reference applied thereto 35 in the different views in the drawings, in which—

Figure 1 is a front view of my improved 40 radiator cap-device, a portion thereof being broken away and shown in cross section.

Figure 2 is a top plan view of Figure 1, a portion of the cover-plate being broken away.

Figure 3 is an end view taken in the direction indicated by the arrow 3 in Figure 1.

Figure 4 is a vertical central sectional view taken on the line 4—4 in Figure 2.

Figure 5 is a sectional view taken on the line 5—5 in Figure 2.

My improved radiator cap-device comprises a metal body-piece A provided with the usual bore which is suitably threaded to be screwed down on the standard type of 55 radiator nozzle 1.

The said body piece is provided with an

internal annular shoulder which has the beveled annular face A¹ and the annular flat seat A². Adapted to rest on the seat A² is a gasket or pack ring B which may be made 60 of rubber or of a leather composition. Hingedly connected to the integrally formed lug A³ (see Figure 4) is a metal cover plate C, which may be of the contour shown in the top plan view in Figure 2. Formed integral with the underside of this cover plate is a seat C¹ which registers with and makes close contact with the pack ring when the plate is disposed at the lowered or closed 65 position.

This cover plate constitutes a closure element for the body-piece, and a support for the moto meter device D which is suitably secured by a usual bolted and sealed connection. At the forward portion of the cover plate is the integrally formed tongue C² (see Figure 2) which registers with a boss A⁴ formed integrally on the body piece. A transverse recess or opening C³ is formed 70 in said tongue.

Disposed in a recess G in the upper portion of boss A⁴ is a threaded stem E whose lower end is journaled on the cross pin E'. On the stem E is the burr F. The stem E when swung up to the vertical position occupies the opening C³ of the cover plate 75 (see Figure 2). By then screwing down the burr F the cover plate is pressed downwardly and is retained securely at sealed contact with the said pack ring. My invention comprises means to fasten the body piece to the radiator nozzle, and a device 80 adapted to be connected to the said body piece to close the opening or recess in which the said fastening means is contained, and which said device becomes locked when it is placed at connected position.

The combination, form, and detail of the several parts for carrying my invention to effect, are as follows: Through the boss A⁴ 85 is a horizontal threaded bore A⁵ into which bore is screwed a set screw H made preferably of iron or steel. This set screw has pointed inner end, and its outer portion is provided with a recess H¹ that is angular in cross section, and adapted to receive a wrench. Any suitable form of socket wrench may be used to turn or drive the said set screw H inwardly until it has 90 tightly engaged the threaded nozzle 1. Adapted to be screwed in the said bore and to close it so as to prevent unauthorized 95 100 105 110

access to the set screw H, is a threaded closure stud J. This stud J is provided with a plate-like head K which may be of the form and may have a monogram initial 5 or fanciful adornment, as shown in Figure 1. Near the end of the said stud J is a diametrically disposed recess J¹ of suitable depth substantially as shown in Figure 4. Adapted to be disposed in this recess is a 10 slug L. Extending downwardly from bore A⁵ is a well A⁶ so located with reference to the set screw H that when the said set screw will have been screwed into the set position at imbedded contact with the nozzle 1, as 15 shown in Figure 4; the said well has been passed and is "in the clear" as shown in Figure 4. Thus, the cap device is secured to the nozzle of the radiator. Before starting the stud J into the bore A⁵ the slug L 20 is inserted into the recess J¹. When the stud J will have been screwed into the position shown, the slug L will have dropped in the well as above described. The stud J is then immovable. Force applied to the 25 head plate K may break off the plate, but with the stud J held by the slug L, the stud is incapable of being removed from the bore, and it constitutes a locked guard against access to the set screw H.

30 It is apparent that the radiator cap-device so fastened, is secured against theft.

Access to the radiator nozzle for the purpose of introducing water to the radiator, is easily had by unscrewing the burr F and 35 swinging down the stem E. The cover plate may be swung on its hinge to full open position. Occasion or necessity ever to detach the body-piece from the radiator nozzle, for any purpose, is remote. However, 40 in case of necessity for detachment or removal of the body-piece, the radiator may be disconnected from its fastenings, and moved to inverted position, causing the slug L to slip or drop from the well A⁶, and 45 which permits the stud J to be easily unscrewed and removed. It is obviously then an easy matter to apply the socket wrench to and retract the set screw H. While the embodiment of my invention, as above described, is of the preferred form, it is understood that minor changes may be made 50 in the structure and arrangement and detail of the several parts of my improved cap-device, within the scope of the invention as defined by the appended claims, 55 without in the least departing from the nature or spirit of my invention.

What I claim as my invention and desire to secure by Letters Patent, is:—

60 1. A radiator cap-device comprising a body-piece adapted to rest on the radiator nozzle and having a cavity in its wall, a tightening means in the cavity operable to fasten the body-piece to the nozzle, a device 65 operable to close the said cavity and to be

come locked when the cap device is at the upright position, but which device operates to unlock when the position of the radiator is inverted.

2. A radiator cap device comprising a 70 body-piece adapted to rest on the radiator nozzle and having a cavity in its wall, a threaded stud in the cavity capable of being screwed to tightened engagement with the radiator nozzle, a device operable to close 75 the cavity and to become locked when the cap device is at the upright position, but which becomes unlocked when the radiator is in inverted position.

3. A radiator cap device comprising a 80 body-piece adapted to rest on the radiator nozzle and having a cavity in its wall, a threaded stud in the cavity capable of being screwed to tightened engagement with the radiator nozzle, a device operable to close 85 the cavity and to become locked when the cap device is at the upright position.

4. A radiator cap-device comprising a body piece provided with threaded bore and having a cavity in its wall, a threaded stud in the cavity capable of being screwed to tightened engagement with the nozzle piece upon which the cap device may be applied, a device operable to close the cavity and to become locked when the cap device is at the 95 upright or vertical position, but which device becomes unlocked and capable of being removed when the cap-device is in the inverted position.

5. A cap-device for automobile radiators 100 comprising a body-piece adapted to be screwed on the radiator nozzle, a threaded stud screwed through a bore in the body-piece and to tighten against said nozzle, a well extended at an angle from the said bore, a closure-piece to be screwed into the outer position of said bore, there being a recess in the said cavity, a slug carried in the said recess and adapted to drop into the said well, the depth of said well being such 105 that a portion of the slug retains its engagement with the recess of the closure piece.

6. A cap-device for automobile radiators, 110 comprising a body-piece adapted to be screwed on the radiator nozzle, a threaded stud screwed through a bore in the body-piece and to tighten against said nozzle, a well extended vertically from said bore and at location clear of the said stud when at 115 its tightened position, a closure-piece to be screwed into the outer portion of said bore and having a recess therein at such location that when the closure piece is screwed into position the recess is at registration with the said well, a slug carried in said recess and adapted to drop into engagement with the said well when the cap device is at the upright position.

7. A cap-device for automobile radiators 120 comprising a body-piece adapted to be 125

screwed on the radiator nozzle, a threaded stud screwed through a bore in the body-piece, a well cavity opening from said bore and at a location clear of the stud when at 5 its tightened position, a closure piece having a head plate and being provided with a recess therein at such location that when the closure piece is screwed into position the head plate is at registration with the outer 10 surface of the body piece and the recess is at registration with the said well, and a slug carried in said recess adapted to drop into engagement with the said well when the cap device is at the upright position, and which 15 slug will drop to position clear of the well, when the cap device is moved to an inverted position.

8. A radiator cap device, comprising a body piece adapted to rest on the radiator 20 nozzle, means to fasten the body piece to the said nozzle, a device adapted to be connected to the said body piece and to close the opening in which said fastening means is contained, and which device becomes locked 25 when it is placed at connected position.

9. A radiator cap device, comprising a body piece adapted to rest on the radiator

nozzle, means contained in the body piece to fasten the body piece to the nozzle, a device adapted to be connected to the said body piece to close the opening in which said fastening means is contained, and which automatically becomes locked when it is placed at connected position, and which becomes unlocked when the position of the radiator 30 35 is changed from the vertical position.

10. A radiator cap device, comprising means contained in the body of the cap to fasten the latter directly to the radiator nozzle, a device to close the opening through 40 which the fastening means has been passed and which device becomes locked when it is placed in the connected position.

11. A radiator cap device comprising a body piece adapted to rest on the radiator 45 nozzle, a fastening means threaded through the said body and to engagement with the said nozzle, and a device to close the opening through which said fastening means has been passed and which becomes locked when 50 inserted at its position.

In testimony whereof I affix my signature.

MILO D. RATHBUN.
